2 Sheets-Sheet 2

UNITED STATES PATENT OFFICE

FREDERICK C. ALEXANDER, OF WEST COLLINGSWOOD, NEW JERSEY

DEVICE FOR FACILITATING THE MANUFACTURE OF PAPER PADS

Application filed November 18, 1930. Serial No. 496,531.

This invention relates to a device for use in the assembling and securing together of paper sheets for the formation of writing pads or tablets.

5 The primary object of the present invention is to provide a device whereby the paper sheets may be conveniently assembled and held with their edges in the proper alignment for the application thereto of glue or cement.

10 Another object of the invention is to provide a device of the above described character, which is adapted to firmly secure the paper sheets together and hold them in such condition while a binding cement is applied to the edges thereof.

15 A further object of the invention is to provide a structure for the purpose above described, which is of simple but strong and durable construction and easy to operate.

20 The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

25 In the drawings:

Figure 1 is a vertical sectional view 30 through the structure embodying the present invention, the section being taken upon the line 1—1 of Figure 2.

Figure 2 is a view in side elevation of the device.

40 Figure 3 is a vertical sectional view through the structure upon the line 3—3 of Figure 4 looking in the direction of the arrows and showing the leaf holding mechanism in working position.

45 Figure 4 is a view in side elevation of the device as shown in Figure 3.

Figure 5 is a sectional view taken upon the line 5—5 of Figure 3.

50 Figure 6 is a view in side elevation of the device showing the manner in which it is ar-

ranged while having sheets stacked therein.

Figure 7 is a view in rear elevation of the device showing the removable door in the back thereof.

55 Referring more particularly to the drawings, wherein like numerals of reference indicate corresponding parts throughout the several views, the numeral 1 generally designates the press device embodying the present invention. This device, as shown, is in the 60 form of a relatively shallow rectangular cabinet having the side walls 2, the front and back walls 3 and 4 respectively and the top wall 5.

65 The back wall 4 has a door opening 6 therein which is closed during the filling of the press by the door 7, which is held in closed position by latch members 8. Above the door 7 the back wall 4 has secured thereto a bracket 9 with which is engaged the 70 hooked end of a brace or support leg 10 when the device is to be stood up in the inclined position shown in Figure 6 while it is being loaded. The upper end of the brace 10 which is hooked or curved to engage in the apertured bracket plate 9, is indicated by the 75 numeral 11.

80 Each side wall 2 has formed therethrough, directly beneath the top 5, an opening 12 and a flange 13 extends inwardly from each side wall at the bottom of each opening as shown in Figures 1 and 3. Each of these openings 12 has mounted therein a bearing block 14, one edge of which is beveled slightly, as shown, and has positioned thereagainst a wedge block 15. In actual practice the inclined contacting surfaces between the bearing blocks 14 and the wedge blocks 15 are very slight so that the wedges 15 may be 85 shifted from below the bearing blocks 14 to the top thereof in order to shift the bearing blocks as desired and without making it necessary to turn the bearing blocks over. The inclination of the contacting beveled faces of the bearing and wedge blocks, as shown 90 in the drawings, is greatly exaggerated in order to clearly bring out the fact that there does exist a slight bevel upon these surfaces.

95 The bearing blocks 14 have extended there-through the eccentrically positioned trun-

nions 16 which are carried by the press bars or eccentrics 17.

These eccentric press bars extend from one bearing block to the other through the top of the cabinet, in the manner shown, and their rotation is facilitated by the hand wheels 18 mounted upon the outer ends of the trunnions 16.

The cabinet is provided with spacing blocks 19 at the sides thereof which may be employed to support and hold in spaced relation the false bottoms 20. It will of course be seen, as the description of the operation of the device is given, that these false bottoms 20 may be removed if the stack of sheets 21 is of such a height that it will fill the interior of the cabinet. If there is only a small stack of sheets to be pressed then the false bottoms 20 may be mounted in position, in the manner shown, between the spacing blocks 19 so as to bring the top of the stack into close proximity to the eccentric press bars 17.

When a stack of papers is placed in the press, as shown in Figures 1 and 3, the press bars 17 are turned so that they will be raised above the center of rotation of the trunnions and, at the same time, the wedge blocks 15 are inserted between the lower edges of the bearing blocks and the flanges 13 at the bottoms of the openings 12. After the stack of paper sheets has been placed in position there is placed thereon a press board 22, and the wedge blocks are then shifted from the bottom to the top of the bearing blocks as shown in Figure 3. It will be seen that upon then rotating the hand wheels 18 the eccentric press bars will be turned down against the press board 22 and will firmly compress the stack of paper sheets.

It will, of course, be understood that as the paper sheets are placed in position in the cabinet upon one of the false bottoms thereof or upon the main bottom, the cabinet will be supported in the inclined position shown in Figure 6 by the supporting leg 10 and the inner edges of the sheets will thus be positioned against the door which forms a portion of the back wall of the cabinet. After the sheets or papers have been compressed in the manner described, the cabinet is set upright and the door 7 removed thus exposing the inner edges of the sheets so that a suitable glue or cement may be applied thereto. After the application of the glue or cement the same is allowed to dry before removing the pressure exerted upon the sheets by the eccentric bars 17, after which the stack of sheets may be removed and divided into pads of suitable thickness to which backs may then be applied.

Having thus described my invention, what I claim is:

1. A device of the character described for compressing paper sheets for the formation

of tablets, comprising a cabinet having a removable side wall section, an eccentric bar extending transversely of the upper portion of the cabinet, means in the side walls of the cabinet for rotatably supporting said bar, and means for vertically shifting the bar supporting means, said bar being designed to compress a stack of paper sheets placed within the cabinet against the removable wall section to hold the same in position following the removal of said wall section.

2. A device of the character described for securing paper sheets in position for the formation of pads, comprising a cabinet having a bottom and side walls and further having a front and a rear wall, said rear wall having a removable section, a bearing block shiftably mounted in each side wall adjacent the top thereof, removable elements each engaging an edge of a bearing block for facilitating the raising or lowering thereof, a bar disposed transversely of the upper portion of the cabinet between said bearing blocks, supporting trunnions extending eccentrically from the ends of said bar and rotatably mounted in the bearing blocks, and means for rotating the bar for effecting the compression of a stack of paper sheets arranged between it and the cabinet bottom and against the removable wall section.

3. A device of the character described for securing paper sheets in position for the formation of pads, comprising a cabinet having a bottom and side walls and further having a front and a rear wall, said rear wall having a removable section, a bearing block shiftably mounted in each side wall adjacent the top thereof, removable elements each engaging an edge of a bearing block for facilitating the raising or lowering thereof, a bar disposed transversely of the upper portion of the cabinet between said bearing blocks, supporting trunnions extending eccentrically from the ends of said bar and rotatably mounted in the bearing blocks, means for rotating the bar for effecting the compression of a stack of paper sheets arranged between it and the cabinet bottom against the removable wall section, and a false bottom adapted to be positioned in the cabinet at different heights above the main bottom thereof to support paper stacks of different heights.

4. In a device of the character described for use in the formation of paper pads, a cabinet having front, back and side walls, said front wall being open and said back wall having a removable section, said side walls each having an opening therein adjacent the top of the cabinet, an inwardly extending flange formed integral with each side wall at the bottom of the opening therein, a bearing block mounted in each side wall opening upon said flange, a removable wedge member interposed between an edge of each bearing block and an adjacent edge of the opening, a

press bar extending transversely of the cabinet between said bearing blocks, a trunnion forming an eccentric continuation of each end of said bar and passing through a bearing block, means upon the outer end of a trunnion for rotating the bar, and a vertically adjustable bottom for the cabinet for the support of a stack of paper sheets beneath said press bar.

5. In a device of the character described for use in the formation of paper pads, a cabinet having front, back and side walls, said front wall being open and said back wall having a removable section, said side walls each having an opening therein adjacent the top of the cabinet, a bearing block mounted in each side wall opening, a removable wedge member interposed between an edge of each bearing block and an adjacent edge of the opening, a press bar 10 extending transversely of the cabinet between said bearing blocks, a trunnion forming an eccentric continuation of each end of said bar and passing through a bearing block, means upon the outer end of a trunnion for 15 rotating the bar, a vertically adjustable bottom for the cabinet for the support of a stack of paper sheets beneath said press bar, and means connected with the back wall of the cabinet for supporting the same in inclined 20 position during the insertion of paper sheets 25 through the open front wall thereof.

6. A paper pad forming device, comprising a structure having spaced parallel side members and a wall connecting said members and 30 provided with a removable door, means vertically adjustable between said side members for supporting a stack of paper sheets against said door, and a rotatable eccentrically mounted pressing member disposed transversely of the wall and supported by the side 35 members thereof designed to apply pressure to the sheets on the said supporting means.

7. A paper pad forming device, comprising a structure having spaced parallel side 40 wall members and a wall between said members, a plurality of block members disposed one above the other against the inner face of each of said side walls, a shiftable bottom for the structure designed to be located at a 45 selected elevation between certain of said blocks, a bearing unit mounted in the upper part of each of said side walls, a bar member disposed transversely of the upper part of the structure, supporting trunnions for said 50 bar each extending eccentrically from one end thereof and each being supported by a bearing element, and means for effecting rotation of said bar for compressing a stack 55 of paper sheets arranged upon said shiftable 60 bottom.

In testimony whereof I hereunto affix my signature.

FREDERICK C. ALEXANDER.
